SAFETY PIN

John H. Todd, Cleveland Heights, Ohio

Application October 28, 1947, Serial No. 782,539

5 Claims. (Cl. 24—156)

1

The invention relates to improvements in safety pins, and is particularly illustrated in the accompanying drawings and described in the instant specification by applications of different forms thereof to the fastening thereby of laundry nets. The laundry nets fastened by the improved safety pins are containers for garments which are stored in the nets and the latter tumbled in the wash wheels to wash the garments.

The claims of the instant application are directed to the form of the invention shown in Figure 7.

It is well known in the laundry art that the washing of many articles in large scale operations is effected in so-called nets, which are made of flexible reticulated material, and each of which contains all or a portion of the articles belonging to one customer, which nets are fastened at their tops or mouths by safety pins. Many of these pins are of so-called giant size, four or five inches in length or even longer. The pins are subjected to considerable pounding or other abuse in the wash wheels or barrels in which the washing is effected.

Many of the laundry nets now being used are made of synthetic material, such as rayon, and are much less bulky and lighter than those made of natural material. However, it is still advisable to use the large safety pins for fastening the lighter nets inasmuch as the pins are subjected to the considerable pounding and abuse mentioned and as secure a fastening of the net as possible is desired despite the effect on the pin of the pounding which it receives. Moreover, even the large pins are frequently sprung open during the washing operation permitting the contents of the net to escape and resulting, if two or more pins are opened in the same wash wheel, in the intermingling of articles belonging to different customers and, consequently, in imperfect distribution of the articles to the real owners thereof with consequent claims upon the laundry for losses and damage. Furthermore, the net material often becomes entangled between closely adjacent portions of the safety pins requiring additional tedious untangling operations and resulting in damage to the nets. The described entangling of the net takes place adjacent both ends of the stem or pinning portion of the pin.

The instant improvements provide means for preventing the springing open of the pins and also the entanglement of the net between closely adjacent parts of the pin.

2

The annexed drawings and the following description set forth in detail certain pin assemblies and special elements illustrating the improvements in safety pins, the same being described and illustrated, however, in only a few of the various forms in which the principle of the invention may be embodied.

In said annexed drawings:

Figure 1 is a side elevation showing improvements in a laundry pin which are designed to prevent the entanglement of a laundry net in the coils of a bent spring wire pin, a portion of a net fastened by the pin being also shown, the net being one which is made of flexible reticulated material and is of relatively light weight and bulk so that, when its opening edge has been closed by the usual operation of repeatedly whipping the stem of the pin over such opening edge, and the successive net folds closely bunched, the net does not cover the whole length of the stem or pinning portion of the pin, and is resiliently mounted on a spring or barrier preventing its entanglement in the pin coils;

Figure 2 is an elevation, in open position, of the pin shown in Figure 1;

Figure 3 is a transverse section, upon an enlarged scale, taken in the plane indicated by the line 3—3, Figure 2;

Figure 4 is an elevation, upon an enlarged scale, taken from the plane indicated by the line 4—4, Figure 2;

Figure 5 illustrates the application to a standard pin of a compression spring designed to prevent the entanglement of a laundry net in the coils of the pin;

Figure 6 is a fragmentary elevation illustrating modified means for preventing the entanglement of the net in the pin coils;

Figure 7 is an elevation of a form of improved laundry pin by which a light, flexible, reticulated laundry net is fastened, a fragmentary portion of the net being shown, and the form of invention shown obviating the entanglement of the laundry net at both ends of the pin stem, i. e., both entanglement in the coils of the pin and also between the inner pinning end and the pin head seat in which the pinning end is held, the view also illustrating net material forced down on the upper side of the pinning end, by the play of the pin elements during the laundry operation, and tending to prevent the pinning end being sprung open during the washing operation;

Figure 8 is a transverse section, upon an en-

larged scale, taken in the plane indicated by the line 8—8, Figure 7;

Figure 9 is a transverse section, upon an enlarged scale, taken in the plane indicated by the line 9—9, Figure 7;

Figure 10 is a fragmentary elevation, partially in section, of a modified form of pin designed to prevent the entanglement of the net between the extreme pinning end and the pin head seat in which the pinning end is held;

Figure 11 is a fragmentary elevation of the head end of a standard pin which has been reorganized, and to which a member has been added, to prevent the entanglement of the laundry net in the head end of the pin, and the opening of the pinning end during the washing operation;

Figure 12 is a transverse section taken in the plane indicated by the line 12—12, Figure 11;

Figure 13 is a longitudinal section taken in the plane indicated by the line 13—13, Figure 11; and

Figure 14 is a fragmentary elevation of the body and seat portion of a pin in which the spring wire is additionally reinforced so as to permit the use of a spring wire of smaller cross-section, the form of invention shown in this figure also preventing entanglement of the net material in the wire coils and between the seat and the pinning end of the pin, and having means for preventing the springing open of the pinning end.

Referring to the annexed drawings in which the same parts are indicated by the same several numbers in the respective figures, there are disclosed several forms of devices in which the invention is embodied. One of these forms, Figures 1 to 6, shows means for preventing the entanglement of the material of which the laundry net is made in the coils of the U-shaped spring wire pin, both in a new pin and also in an old pin which has been reorganized to contain the improvement and prevent such entanglement.

Another form of the invention is shown in Figures 7 to 9, in which means are provided for preventing entanglement of the material of which the laundry net is comprised both in the coils of the U-shaped spring wire pin and also between the pinning end of the pin and the seat within which said pinning end is held, means also being shown for preventing the springing open of the pinning end during the washing operation.

Another form of the invention is shown in Figure 10, in which modified means are provided for preventing entanglement of the net material between the pinning end of the pin and the seat for such pinning end, means also being shown for preventing the springing open of the pinning end.

Another form of the invention is shown in Figures 11, 12, and 13, in which a standard pin is reorganized to prevent entanglement of the material of the laundry net between the pinning end of the pin and the pin seat, and to prevent the springing open of the pinning end.

A form of the device is shown in Figure 14 containing the above-mentioned improvements in a laundry pin which is reinforced so as to permit the use of a spring wire of smaller cross-section.

Referring particularly to Figures 1 to 5, a standard form of so-called giant safety pin is shown having a plate-like head 1 with a curled peripheral edge 2 forming a flange, which flange is inwardly-extended on the pinning end side of the head 1 and disposed in a plane laterally of

and substantially parallel to the face of the head 1 to form a seat 3 providing a pocket for receiving the pinning end 6. The vibratory or bobbing movements of the pinning end 6, during the washing operation, are toward and from the seat 3 and adjacent laterally of the plate-like head 1, as will be understood from Figure 8 which shows a transverse section of a pin head having conventional body and pinning end elements similar to those shown in Figure 1. The shank 4 of the pin has a curved outer end which is rigidly secured in the curled outer head edge 2 up to a point adjacent the seat 3 and is tensioned by means of coils 5 intermediate its ends to provide a firm engagement of the pinning end 6 in the seat 3. In usual practice, a ring 7 is passed loosely through the pin coils 5 and also through a uniquely configured check member 8 provided with special indicia, such as a particular number (not shown), for establishing identification of the owner of the contents of the laundry net 15 which are being washed.

It has been stated that the laundry nets 15 of synthetic material are lighter in weight and considerably less bulky than standard nets made of natural material. It also has been stated that it is necessary to utilize a large laundry pin for closing the mouths of these synthetic nets because a comparatively large pin is necessary to withstand the pounding which the assembly receives in the tumbler or wash wheel. Therefore, when the mouth of the synthetic net 15 is adequately closed by a close grouping of the net folds 16 made by whipping the pinning end 6 over the material of the net mouth, there is a considerable length of the pinning end 6 which is not covered by the net folds 16. The invention shown in Figures 1 to 5 provides means for resiliently keeping the net folds 16 in proper closed position and for preventing these folds from becoming entangled in the coils 5 of the pin due to creeping of the net folds 16 between these coils as the latter play during the washing operation.

The means for accomplishing the advantages just mentioned comprise a compression spring 10 having an elongated hook 11, Figs. 1, 2, 4 and 5, which is passed around one of the coils 5 and tightly secured thereto by a pressed fit, the other end 12 of the spring 10 being ground on its exterior surface and closely disposed to the adjacent coil of the spring 10, this end 12 of the spring 10 engaging the pinning end 6 with a sliding fit, all as appears in Figures 2 and 3. The two ends of the spring 10 are of reduced size in cross-section thus providing an enlarged intermediate section 13. The pinning end 6 of the safety pin is passed through the entire spring 10.

It is evident that the described structure provides a resilient mounting for the closed laundry net 15 which keeps the mouth of the latter adequately closed by forcing the folds 16 toward and against the inner lower edge of the head 1, and also provides accommodation for different amounts of bulk of the closed net mouths and for any play to which the closed mouth is subjected during the washing operation. The reticulated synthetic net material is also flexible or stretchy whereby it is materially expansive or materially compressible. The effect of this natural springiness of the net material is balanced by the play of the spring elements during the washing operation.

The spring 10 incorporated with the laundry pin, as shown in Figures 1 to 5, may be a separate

member provided for standard pins and connected thereto as shown, or it may be an element of an entirely new pin made for the stated purpose and incorporated with the remaining elements of the pin as shown.

In Figure 6 I disclose a standard pin 4 reorganized for preventing entanglement of the material of the laundry net in the coils 5 and the reorganization consists in securing to the pinning end 6 with a pressed fit a closely coiled bushing 17 adjacent the spring coils 5.

Referring to the form of the device shown in Figures 7, 8, and 9, provision is made not only for preventing entanglement of the material of the laundry net 29 in the coils 24 of the pin 23, but means also are provided for preventing entanglement of the net material between the pinning end 25 and the pin seat 22. Similarly to the pin 4 shown in Figures 1 to 5, the pin 23 is held by plate-like head 20 and a curled flange 21 formed at the top end to hold the shank end of the pin 23 and at the other end to provide a seat 22 for the pinning end 25, the pin 23 also being formed with an intermediate coil portion 24. The plate head 20 is disposed laterally of the path of vibratory and bobbing pin movements due to the washing operation, as clearly appears in Figure 8.

The form of the safety pin shown in Figures 7, 8, and 9 is a new pin having a shank 23 and an indentation 28, Figures 7 and 8, in the exterior surface of the seat 22 for the pinning end 25. The indentation 28 thus provides a raised longitudinally-narrow transverse support 33 for the pinning end 25 and within the seat 22. This support 33 is substantially a line-contact support.

The raised pin support 33 thus provides a longitudinal recess 34 disposed beneath the pinning end 25 and extending from the raised projection 33 to the inner end of the seat 22. If folded net material creeps into this recess 34 during the washing operation, it will be held only lightly by the pinning end 25 since the recess is always open and cannot be entirely closed by the pinning end. Therefore, there will be no continuous creeping of the net material into the recess 34 and no constantly-increasing accumulation of net material in the seat beneath the transversely-adjacent portion of the pinning end 25. If the net material could not readily pass in and out of the recess 34, it would creep in under that part of the pinning end 25 mounted on the projection 33 as this pinning end 25 bobs up and down during the washing operation.

Thus, the vibrations of the pinning end 25 will not cause the latter firmly to catch the net material. When, in present standard structures, the material creeps in between the base of the seat 22 and a pinning end portion of the pin which engages the bottom of the seat throughout its length, the net material is firmly held by the pinning end portion and gradually creeps further inwardly within the seat to become tightly entangled. In the improved pin herein shown and described, this disadvantage is obviated by the raised support 33 providing the recess 34 within which the net material is not firmly held between the pinning end 25 and the bottom of the seat 22.

Furthermore, there is shown in Figures 9 and 10 the manner of forcing the pinning end 25 against its raised support 33 within the seat 22, thus preventing the release of the pinning end from the seat 22 during the washing operation and the slipping off of the net 29 from the pinning end 25 and, consequently, the escape from

the net 29 of the articles therein contained and being washed. These means restraining and minimizing the springing or bobbing open of the pinning end 25 comprise an element 32, such as shown in Figures 7 and 9, which is provided by longitudinally lengthening the upper portion of the head 20 to an extent so that a lower folded edge 27 of the extension 32 restrains the size of the outer folds 30 and 31 of the folds 26 into which the mouth of the net 29 has been whipped in assembly of the net of the pin. Thus the outer terminal folds of the net 29 are compressed into the wedging or diminishing space 19 formed by the break or opening of the inner head edge beneath the rolled edge 27 of the longitudinal extension 32 by the play of the elements and the tension of the spring 10. This assembly exerts considerable pressure through the folds 30 and the adjacent folds 31 upon the pinning end 25 and greatly limits and minimizes the amplitude of the vibrations of the pinning end 25 during the washing operation. In fact, this amplitude of the pinning end vibration is limited to an extent that obviates the springing of the pinning end 25 out of the seat 22 and thus obviates the opening of the pinning end. The peripheral edge 18 of the head 20 is curved downwardly toward the seat 22 so as to provide a space 19 of gradually downwardly-increasing longitudinal dimension whereby one or two or a small number of the folds 30 of the net 29 and adjacent folds 31 are wedged into the space 19 and pressed downwardly upon the pinning end 25 so as firmly but somewhat resiliently to hold the pinning end 25 to its mounting 33 and prevent its being sprung out of the seat 22.

A modification of the means for preventing creeping of the folded net material into the pin seat between the seat base and the pinning end is shown in Figure 10, wherein the bottom of the seat 38 is slightly curved upwardly at its outer end to form a support 39 for the pinning end 25 within the seat 38, and then is curved sharply downwardly to its inner terminal edge into a flaring end portion 36, thus forming a recess 37 adjacently below the adjacent portion of the pinning end 25. If and when the net folds 30 and 31 creep into this recess 37, they will only be loosely engaged therein and only lightly held so that they will not become entangled between the pinning end 25 and the adjacently lower bottom surface of the seat 38. Therefore, there will be no continuous creeping and continuous accumulation of the net material in the seat 38 below the pinning end 25.

Referring to the form of invention shown in Figures 11, 12, and 13, the same is an entirely reorganized standard laundry pin, insofar as preventing entanglement of the net material between the pinning end 25 and the seat 22 is concerned, and insofar as the preventing of the opening of the pinning end 25 is concerned. In other words, the standard pin is reorganized not only to provide the raised member 33 supporting the pinning end 25 and the consequent longitudinal recess 34 but also is provided with an element 41 adjacent the inner edge of the head 20 which extends substantially half way across the head from one side to the other and has a bottom outwardly sloping surface portion. This element 41 compresses the folds of the net mouth adjacent the seat 22 and wedges them toward the pinning end 25 and thus shortens the amplitude of the play of the pinning end 25, during the washing operation, so that this pinning end

25 does not become disengaged from the seat 22. This special element 41 is a loop member, Figure 12, the abutting edges of which are welded together adjacently above the pin 23 adjacent the top of the head 20; and, also, the loop element 41 is welded to the top of the pin 23 at its two side edges, as clearly shown by the welds 42, Figures 11 and 12. This element 41 is engaged with the pin head 20 by means of notching a bottom peripheral edge portion of the element 41, as indicated by the number 40, Figure 13, and the head 20 is seated in this notch 40.

Referring to the form of the invention shown in Figure 14, provision is made for securing suitable wire strength from a wire of smaller cross-section. This result is obtained by extending the flange 21 of the head 20 to provide a tubular formation 43 enclosing and secured to the wire 23 for a considerable portion of the length of the latter and by also providing the wire 23 with an upwardly-extended lug 44 passing through a hole 45 formed in the tube 43 so as to prevent lengthwise movement of the wire 23 relatively to the head 20, the structure thus reinforcing the wire 23 and permitting the use of a wire of smaller cross-section.

Inasmuch as a safety pin is used in different positions, the directions and relative positions of the different elements of the safety pin are arbitrarily herein defined as follows:

The term "longitudinal" indicates a direction parallel to the axis of the pinning end of the safety pin.

The term "transverse" means a direction at substantially right angles to the plane of the pin head 1 and the pin head 20.

The word "outwardly" means toward the curved end of the stem 4 or the stem 23 which are fixed in the flanges of the respective plate heads 1 and 20, this direction thus indicated by the word "outwardly" being parallel to the plate heads 1 and 20.

The word "inwardly" means a direction opposite to that defined as applying to the word "outwardly"; in other words, a direction away from the curved fixed end of the stem 4 or the stem 23 and also parallel to the plate head 1 or the plate head 20.

The word "laterally" means the same direction as the word "transversely," and the word "exterior," as applied to the pin seat, means the lower surface of the pin seat, as the latter is shown in Figures 1, 7, 8, 10, 11, and 14. The word "interior," as applied to the pin seat, means the upper surface of the seat, as it appears in Figures 1, 7, 8, 10, 11, and 14.

What I claim is:

1. A safety pin, for fastening laundry wash nets, having a head formed with a longitudinally-extending pinning end seat, a spring wire secured at one end to the head and having an opposite pinning end engaging the seat in the closed position of the pinning end, the spring wire being formed with a tension coil formation intermediate its ends, the head structure forming the seat having a transversely-extending projection therein intermediate its ends, said projection extending into the path of the vibratory movements of the pinning end during the washing operation, upon which projection the pinning end rests in its closed position, the projection thus providing a longitudinal recess extending therefrom to the inner end of the seat structure, said recess being disposed beneath the portion of the pinning end inwardly of and adjacent to the transverse pro-

jection, whereby pinned folded net material entering the recess during the washing operation will be only lightly held by the pinning end and can move in and out of the recess during the vibratory movements of the pinning end due to the washing operation, thus obviating continuous creeping of the net material into the recess and the accumulation of this material in the seat beneath such portion of the pinning end of the pin inwardly of and adjacent to the transverse projection.

2. A safety pin, for fastening laundry wash nets, characterized as in claim 1, in which the projection is formed by an exterior transversely-indented portion of the head structure forming the seat, to provide a transverse longitudinally-narrow pin mounting in the seat.

3. A safety pin, for fastening laundry wash nets, having a flanged plate-like head formed adjacent one transverse side with a pinning end seat, a spring wire of which one end engages the seat in the closed position of the pinning end, the wire being secured at its opposite end in the flange and adjacent the opposite side of the head, the spring wire being formed with a tension coil formation intermediate its ends, the head being disposed adjacent to and substantially parallel to the path of vibratory movements of the pinning end during the washing operation, abutment means mounted on the pinning end adjacent the tension coil formation, the lower portion of the inner end of the head being cut away to provide a wedging break therein adjacent the seat, whereby folded net material intersected by the pinning end, bearing at its outer side on the walls of the head break, and bearing at its inner side on said abutment means, will be forced, by the play of the pin elements during the laundry operation, into the break and transversely down against the pinning end of the pin to minimize the amount of movement of the pin away from its seat.

4. A safety pin, for fastening laundry wash nets, having a flanged plate-like head formed adjacent one transverse side with a pinning end seat, a spring wire of which one end engages the seat in the closed position of the pinning end, the wire being secured at its opposite end in the flange and adjacent the opposite side of the head, the spring wire being formed with a tension coil formation intermediate its ends, the head being disposed adjacent to and substantially parallel to the path of vibratory movements of the pinning end during the washing operation, abutment means mounted on the pinning end adjacent the tension coil formation, the lower portion of the inner end of the head being cut away to provide a break therein adjacent the seat, said break being of increasing longitudinal dimension toward the seat, whereby folded net material intersected by the pinning end, bearing at its outer side on the walls of the head break, and bearing at its inner side on said abutment means, will be forced, by the play of the pin elements during the laundry operation, into the break and transversely down against the pinning end of the pin to minimize the amount of movement of the pin away from its seat.

5. A safety pin, for fastening laundry wash nets, having a head formed with a longitudinally-extending pinning end seat, a spring wire secured at one end to the head and having an opposite pinning end engaging the seat in the closed position of the pinning end, the spring wire being formed with a tension coil formation interme-

diate its ends, abutment means mounted on the pinning end adjacent the tension coil formation, the head being disposed adjacent to and substantially parallel to the path of vibratory movements of the pinning end during the washing operation, the head structure forming the seat having a transversely-extending projection therein intermediate its ends, said projection extending into the path of vibratory movements of the pinning end during the washing operation, said projection forming a narrow mounting for the pinning end in the seat, the projection thus providing a longitudinal recess in the seat beneath the pinning end and between the projection and the inner end of the seat, whereby 15 pinned folded net material entering the recess during the washing operation will be only lightly held by the pinning end, thus obviating continuous creeping of the net material into the recess and the accumulation of this material in the seat beneath the pinning end of the pin, the inner end of the head being cut away adjacent the seat to provide a wedging break therein, whereby folded net material intersected by the pinning end, bearing at its outer side on the walls of the head break, and bearing at its inner side on said abutment means, will be forced, by the

5

play of the pin elements during the washing operation, into the break and transversely down against the pinning end of the pin to minimize the amount of movement of the pin away from its seat.
